Patented Aug. 10, 1976

240,946

BOWLING GAME CABINET

James R. Livesey, Hawthorne, Calif., assignor to
Wolverine Toy Co., Booneville, Ark.

Filed Oct. 16, 1974, Ser. No. 515,144

Term of patent 14 years

Int. Cl. D21—01

U.S. Cl. D34—5 BB

Fig. 2

Fig. 1

FIG. 1 is a perspective view of a bowling game cabinet embodying my new design; and

FIG. 2 is a second perspective view of a bowling game cabinet embodying my new design with a portion of bowling pins shown in an alternate position.

The reverse and side of the bowling game cabinet, which are not shown in the drawings, are plain and unornamented.

I claim:

The ornamental design for a bowling game cabinet, as shown and described.
